(No Model.)

C. F. OWEN.

PRINTING PRESS MOVEMENT.

No. 276,621.

Patented May 1, 1883.

UNITED STATES PATENT OFFICE.

CHARLES F. OWEN, OF CHICAGO, ILLINOIS.

PRINTING-PRESS MOVEMENT.

SPECIFICATION forming part of Letters Patent No. 276,621, dated May 1, 1883.

Application filed September 2, 1882. (No model.)

To all whom it may concern:

Be it known that I, CHARLES F. OWEN, of Chicago, county of Cook, State of Illinois, have invented a new and useful Improvement in Printing-Press Movements; and I declare the following to be a full, clear, and exact description of the same, such as will enable others skilled in the art to which it pertains to make and use it, reference being had to the accompanying drawings, which form a part of this specification.

My invention consists in the combinations of devices and appliances hereinafter specified, and more particularly pointed out in the claims.

15 In the drawings, Figure 1 is an inverted plan view of an apparatus embodying my invention. Fig. 2 is a side elevation of the same, showing parts in section. Fig. 3 is a separate view of the star-wheel shown at the end of the rack. 20 Fig. 4 represents separate views of the end pins.

The object of my invention is to provide a bed and cylinder movement for printing-presses in which the bed is constructed with a 25 rack in which a star-wheel located upon a swinging frame meshes, the star-wheel being operated by the driving gear in such a manner that the bed is propelled to and fro, as desired.

In carrying out my invention, A is a suitable 30 pedestal or arm secured to the frame of the press.

B is the drive gear-wheel.

The shaft b, which carries the drive gear-wheel B, is driven by the driving-shaft of the 35 press by suitable gearing.

C is the bed-plate.

c represents a rack secured to the bed-plate or bed. The device admits of the simplest and most inexpensive form of rack. It may be 40 made, for instance, by inserting a row of steel or iron pins, c³, into the bottom of the bed itself perpendicularly, or be otherwise constructed.

D is a swinging frame, properly secured 45 upon the shaft b. E is a pinion secured to the swinging frame by the shaft e, in such a position that it is adapted to mesh with the drive gear-wheel B. F is a star-wheel secured upon the shaft e, and adapted to mesh with the rack 50 c, secured to the bed of the press. This mechanism is preferably so located that the planes of the gear-wheels and the swinging frame are

horizontal. By this means the motion is applied to the bed very near to its surface, thus obviating the tendency of the bed to tip up at 55 the end of its journey when it butts the bunter-springs. I prefer to unite the two outer pins c³ by a suitable connecting-clasp, c', to give greater strength to the end pin, as it is evident that peculiar strain comes upon it. I 60 also prefer to provide the end pin with a friction-ferrule, c². The star-wheel F is provided with a guide, f, to engage against the curved end C' of the bed when the star-wheel reaches 65 the end of the rack, and cause the swinging frame D to swing over to the other side of the rack, as shown in Fig. 1 by the dotted lines.

In the practical operation of the device there should be a lug or stop on each side of the rack to prevent the swinging frame, with its 70 star-wheel, from swinging too far and getting out of gear when it goes by the end of the rack. This stop may have any suitable location.

The operation of the device will now be understood. The drive gear-wheel B, propelled 75 by the driving-shaft b, meshes with the pinion E, whereby the star-wheel is rotated, and this, meshing with the rack c, causes a movement of the bed-plate C. When the star-wheel reaches the end of the rack it is guided by the guide 80 f, working in the curved end C' of the bed-plate, around on the other side of the rack, as shown by the dotted lines in Fig. 1, producing again the required movement of the bed. It is evident that this form of movement 85 admits of the gear-wheel B having a very great range in diameter. I prefer that the guide f should be provided with a friction-ferrule.

What I claim is—

1. A movement for printing-presses, consisting of the combination, with the bed provided with a rack, of a driving gear-wheel adapted to be driven by a shaft, the swinging frame D, hung upon said shaft, a pinion secured by 95 shafting to said swinging frame, adapted to mesh with the driving gear-wheel, and a wheel driven by said pinion, adapted to mesh with said rack, substantially as described.

2. A movement for printing-presses, consisting of the combination, with the bed provided with a rack, of a driving-wheel adapted to be driven by a shaft, the swinging frame D, hung upon said shaft, a pinion secured by shafting 100

to said swinging frame, adapted to mesh with the driving gear-wheel, and a wheel driven by said pinion, adapted to mesh with said rack, said wheel provided with a guide, substantially as described.

3. The combination, in a printing-press movement, of a bed provided with a rack, a driving-wheel adapted to be driven by a shaft, a pinion carried by the swinging frame, and adapted to engage the driving gear-wheel, and a wheel adapted to engage the rack, and provided with a guide, substantially as described.

4. In a printing-press, a bed provided with a rack constructed of pins secured to said bed, the outer pins provided with a connecting-clasp, and the end pin with a friction-ferrule, substantially as described. 15

In testimony whereof I sign this specification in the presence of two witnesses.

CHARLES F. OWEN.
